Primary Examiner — Lakiya G Rogers*Assistant Examiner* — Carissa C Fitts(74) *Attorney, Agent, or Firm* — Quickpatents, LLC;
Kevin Prince(57) **CLAIM**

We claim the ornamental design for a fishing light, as shown and described.

DESCRIPTION

FIG. 1 is a perspective view of a fishing light, showing our new design;

FIG. 2 is a top plan view thereof;

FIG. 3 is a bottom plan view thereof;

FIG. 4 is a left-side elevational view thereof;

FIG. 5 is a right-side elevational view thereof;

FIG. 6 is a front elevational view thereof;

FIG. 7 is a rear elevational view thereof;

FIG. 8 is a perspective view of a fishing light, showing a second embodiment;

FIG. 9 is a top plan view thereof;

FIG. 10 is a bottom plan view thereof;

FIG. 11 is a left-side elevational view thereof;

FIG. 13 is a front elevational view thereof; and,

FIG. 14 is a rear elevational view thereof.

The broken lines showing a power cord and LED components in the figures depict environmental matter and form no part of the claimed design.

1 Claim, 6 Drawing Sheets(56)
